US0D1078500S

(12) **United States Design Patent** (10) **Patent No.:** **US D1,078,500 S**
Chen (45) **Date of Patent:** **** Jun. 10, 2025**

(54) **LOCATOR**

(71) Applicant: **Shenzhen Sanyi Technology Co., Ltd.**, Shenzhen (CN)

(72) Inventor: **Xiaoquan Chen**, Jieyang (CN)

(73) Assignee: **Shenzhen Sanyi Technology Co., Ltd.**, Shenzhen (CN)

(**) Term: **15 Years**

(21) Appl. No.: **29/935,924**

(22) Filed: **Apr. 4, 2024**

(30) **Foreign Application Priority Data**

Feb. 27, 2024 (CN) 202430097628.2

(51) LOC (15) Cl. **10-04**

(52) U.S. Cl.

USPC **D10/46**; D10/70

(58) **Field of Classification Search**

USPC D10/103, 75, 78, 70; D8/61, 51; D15/122; D14/420

CPC F16L 55/48; F16L 2101/30; G01N 29/28; G01N 29/069; G01N 29/262; G01N 29/225; G01N 29/043; G01N 29/04; G01N 2291/0289; G01N 2291/267; G01N 2291/2634; G01N 2291/2636; G01V 3/15; G01V 3/165; G01V 3/38; G01R 29/0871; G01R 29/0878; H04N 13/239; H04N 13/271; H04N 2213/001; H04N 2013/0081; G06T 7/73; G06T 2207/10021; G06T 2207/30244

(57) **CLAIM**

The ornamental design for a locator as shown and described.

DESCRIPTION

FIG. 1 is a front, right and top perspective view of a locator showing my design;

FIG. 2 is a rear, left and bottom perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof; and,

FIG. 8 is a bottom plan view thereof.

The broken lines are included for the purposes of illustrating portions of the locator that form no part of the claimed design.

1 Claim, 8 Drawing Sheets
